GEORGE GILL, OF TAUNTON, MASSACHUSETTS, ASSIGNOR TO REED & BARTON, OF SAME PLACE.

Design No. 3,989, dated April 26, 1870.

DESIGN FOR A CAKE-DISH

The Schedule referred to in these Letters Patent and making part of the same.

To all persons to whom these presents may come:

Be it known that I, GEORGE GILL, of Taunton, of the county of Bristol and State of Massachusetts, have invented or produced a new, useful, and ornamental Design for a Cake-Dish or Tazza; and do hereby declare the same to be represented in the accompanying drawing, and to be described as follows, such drawing being a front elevation of the tazza.

The bowl A is hat-shaped, or is composed of an annular rim or flange, *a*, and a flaring body, *b*, the bottom of which is slightly convex.

The bowl is supported on a tapering or bell-shaped stem, B, formed as represented, such stem springing

from a cylindrical seat or base, C, from which radiate and incline downward three legs D D D.

The upper part of each leg is a cylinder, having on each end a concavity containing a quartre-foil or rosette.

Each leg at its lower part terminates in a taloned foot, the whole being formed as represented.

I claim as my invention—

The cake-dish or tazza design, substantially as hereinbefore described, and as exhibited in the accompanying drawing.
